ELECTRICAL WIRE HEATING UNIT OR SIMILAR ARTICLE

Herbert E. Peterson, 815 W. Northeast Shore Drive,
McHenry, Ill.

Filed Dec. 4, 1963, Ser. No. 77,657

Term of patent 14 years

(Cl. D26—1)

The single figure is a perspective view of an electrical wire heating unit or similar article showing my new design.

The dominant features of my design are shown in solid lines in the drawing. The conductor wire shown in dash-dot lines is for illustrative purposes only.

I claim:

The ornamental design for an electrical wire heating unit or similar article as shown and described.
